UNITED STATES PATENT OFFICE.

WILLIAM ASA GIBSON, OF PEORIA, ILLINOIS, ASSIGNOR OF ONE-THIRD TO GEORGE B. KOONTZ AND ONE-THIRD TO JOHN C. SCHLEICH, BOTH OF PEORIA, ILLINOIS.

FEED-WATER SYSTEM FOR STEAM-BOILERS.

1,226,502.

Specification of Letters Patent. Patented May 15, 1917.

Application filed March 10, 1916. Serial No. 83,404.

To all whom it may concern:

Be it known that I, WILLIAM ASA GIBSON, a citizen of the United States, residing at Peoria, in the county of Peoria and State of Illinois, have invented new and useful Improvements in Feed-Water Systems for Steam-Boilers, of which the following is a specification.

This invention relates to improvements in feed water systems for steam boilers and especially with reference to the provision of an overhead feed induction valve and heater by means of which feed water is supplied to a locomotive or other boiler, is heated, by being commingled with steam in the steam space of the boiler and is supplied to the boiler in a highly heated condition and commingled with condensed steam so that the feed water is raised to substantially the same temperature as the live steam in the boiler and in this condition is supplied to the boiler by the valve from a point above the water line.

One object of the invention is to provide an improved feed water system for boilers by means of which foaming is prevented.

Another object is to provide improved feed water heating means which obviates danger of boiler explosion.

Another object is to provide improved feed water heating means which effects an economy in fuel.

Another object is to provide improved feed water heating means which prevents crawling of the boiler flues, greatly diminishes the expansion of the sheets and flues, and also diminishes leakage such as is caused by undue expansion of the sheets and flues.

The invention consists in the construction, combination, and arrangement of devices, hereinafter described and claimed.

In the accompanying drawings:

Figure 1 is an end elevation of my improved overhead feed induction and heating valve.

Fig. 2 is a sectional view of the same, showing the valve arranged in the steam space of a boiler, a portion of the boiler being indicated in cross section.

In accordance with my invention, the boiler 1 which may be a locomotive boiler, as here shown, or any other form of steam boiler, is provided with a feed water pipe 2 which leads from an injector or pump of

any suitable form and which is not here shown, to an induction and heating valve 4 which is located on the upper side of the boiler and near the front end thereof, or in other words, is located at a distance from the fire box or furnace. The feed pipe is in practice provided with a check valve of any suitable form to close against back pressure.

The valve 4 has a cylindrical body or barrel 6 provided with an exteriorly threaded portion 7, adapting the valve to be screwed in a threaded opening in the top of the boiler. Any other suitable means may be employed for securing the induction and heating valve in place. The body or barrel 6 is formed with a downwardly contracting feed nozzle 8.

A funnel 9 which forms a steam and water mixing and a speed accelerating element is arranged around and extends downwardly from the nozzle 8 with its major portion in spaced relation thereto, to form a chamber 10, the upper end of the funnel being united to the downwardly tapering wall of the nozzle and being provided with steam intake openings 11. The funnel has its wall progressively thickened downwardly so that the lower end of the chamber 10 is of less diameter than the upper end of said chamber and the funnel is provided near its lower end with discharge openings 12. In the lower end of the funnel is a spreading and speed accelerating cone 13 which is here shown as a plug screw in the lower end of the funnel as at 14. The funnel and the major portion of the nozzle are arranged in the steam space 15 of the boiler, above the water line 16.

The induction and heating valve is here shown as provided with a T-head 17 forming oppositely extending water inlet arms 18 to which the feed water pipe 2 is connected by branch pipes 19. A partition 20 is formed between the inner ends of the arms 18 and a partition 21 extends downwardly in the center of the nozzle 8, below the partition 20. Ports 22 communicate with the arms 18 respectively and with the upper end of the nozzle 8 at opposite sides of the partitions and controlling valves 23, 105 are provided which are arranged to close downwardly and to seat in the ports and by means of which communication may be established or cut off between the feed water pipe, its branches, and the nozzle as will be 110

understood. Each of these valves 23 has an operating stem 24 passing up through a bonnet 25 and a packing nut 26, each stem being provided at its upper end with an operating wheel or handle 27.

The operation of my invention is as follows: When the injector or pump is working and the valves 23 are opened, feed water is forced into and through the nozzle 8 of 10 the induction and heating valve 4. The water is crowded into the nozzle by the partition 21 and owing to the contracted lower end of the nozzle, which acts on the principle of the *vena contracta* and also owing to 15 the pressure of the water and the gravity thereof, issues from the nozzle at high speed. The apex of the spreading cone 13 is a slight distance below the center of the discharge end of the nozzle so that the cone acts to 20 spread the feed water and to accelerate the speed thereof and direct the water to the openings 12. Live steam, at high pressure, in the steam space of the boiler enters the chamber 10 through the openings 11 and be- 25 comes commingled with the feed water as it passes downwardly over the cone. The commingling of the water with the steam in the lower portion of the chamber 10 causes a partial condensation of the steam and 30 hence the velocity of the steam as it enters the openings 11 is very much greater than that of the partially condensed steam, which, together with the water is discharged through the openings 12 and hence the steam 35 forces the feed water, saturated with steam, into the boiler at a point above the water line and owing to the intermediate commingling of the steam with the feed water, the feed water is heated and hence the water in 40 the boiler is kept at approximately the same temperature at all points in the boiler, foaming is prevented, crawling of the flues is prevented, the danger of boiler explosion is very greatly lessened, an economy in fuel is 45 effected, and unequal contraction and expansion of the sheets and flues is prevented, so that leakage is greatly diminished.

Foaming is prevented by my induction and heating valve because the heat imparted to the feed water thereby causes a rapid precipitation of the chlorides and carbonates of calcium and sodium, thus preventing sa-

ponification in the water in the boiler. Moreover, a uniform circulation is caused in the boiler and the steam produced by the 55 boiler is dry.

The valve 23 may be used singly or simultaneously and may be adjusted as required to control the supply of water to the boiler and also to vary the proportions of the feed 60 water as it passes through the induction and heating valves with the live steam supplied thereto from the steam space of the boiler.

Having described the invention, what is claimed is:

1. In a steam boiler feed water system, a nozzle open at its outer end and arranged to discharge in the steam space of a boiler and a structure extending in the same direction as the nozzle and providing a chamber 70 around the discharge end of the nozzle, said structure having a steam inlet opening to said chamber at a point above the discharge end of the nozzle and also having a discharge opening leading from said chamber 75 at a point below the discharge end of the nozzle, and a water spreading and speed accessory element arranged between the said discharge opening of the chamber and a point opposite and spaced from the discharge end of the nozzle.

2. In a steam boiler feed water system, a nozzle open at its outer end and arranged to discharge in the steam space of a boiler and a structure extending in the same direction as the nozzle and providing a chamber 85 around the discharge end of the nozzle, said structure having a steam inlet opening to said chamber at a point above the discharge end of the nozzle and also having a discharge opening leading from said chamber 90 at a point below the discharge end of the nozzle, and a water spreading and speed accessory cone arranged between the said discharge opening of the chamber and a point 95 opposite and spaced from the discharge end of the nozzle.

In testimony whereof I affix my signature in presence of two witnesses.

WILLIAM ASA GIBSON.
